CLOCK DIAL

Filed Nov. 1 1930

Inventor.
Robert J. Eymann
Seymour Earle & Nichols
Attn:

UNITED STATES PATENT OFFICE

ROBERT J. EYLMANN, OF TEANECK, NEW JERSEY, ASSIGNOR TO THE E. INGRAHAM COMPANY, OF BRISTOL, CONNECTICUT, A CORPORATION

DESIGN FOR A CLOCK DIAL

Application filed November 1, 1930. Serial No. 37,500. Term of patent 7 years.

To all whom it may concern:

Be it known that I, ROBERT J. EYLMANN, a citizen of the United States, residing at 210 Vandelinda Ave., Teaneck, in the county of Bergen and State of New Jersey, have invented a new, original, and ornamental Design for a Clock Dial, of which the following is a specification, reference being had to the

accompanying drawing, forming part thereof.

The figure is a face view of a clock-dial showing my new design.

I claim:

The ornamental design for a clock-dial as shown.

ROBT. J. EYLMANN.
